UNITED STATES PATENT OFFICE.

DONALD M. GILES, OF PHILADELPHIA, PENNSYLVANIA, ASSIGNOR TO JOHN H. GILES,
TRADING AS GILES DYEING MACHINERY COMPANY, OF PHILADELPHIA, PENN-
SYLVANIA.

SNUBBING DEVICE FOR DYE STICKS.

Application filed November 11, 1922. Serial No. 300,462.

To all whom it may concern:

Be it known that I, DONALD M. GILES, a citizen of the United States, residing in the city and county of Philadelphia, State of Pennsylvania, have invented a new and useful Snubbing Device for Dye Sticks, of which the following is a specification.

My invention has reference to skein dyeing machines for yarns or like spinnable material, of the Ferris-wheel type, as disclosed in Patent Number 1,146,324 dated July 13, 1915, and is directed more particularly to novel mechanism, hereinafter referred to as a "snubbing device", for permitting 10 turning of the outer dyesticks in one direction and preventing retrograde rotation thereof.

The type of machine referred to includes any machine for chemically treating spinnable material, such as a skein dyeing machine consisting of a dye vat usually semi-cylindrical in shape, a reel revolving in the vat, means for supporting the skeins of yarn on the reel, consisting of two concentric circular series of yarns supporting or dye sticks (on each end of the reel) between which the skeins of yarn are stretched, means for turning the outer sticks, and means for preventing retrograde rotation of the dye sticks. 20 The reel revolves in the dye vat and as each outer stick passes a certain point, it is "tripped" or given a quarter turn so that the position of the yarn on the sticks is constantly changed during the dyeing operation 30 to insure thorough and uniform action thereon by the dyestuff or liquor.

The present invention is directed more particularly to a snubbing device normally to prevent retrograde or reverse rotation of 40 the dyesticks after tripping so as to progressively subject all parts of the yarn to the dye liquor while also being adapted to permit rotation of the dyesticks in the opposite direction, or in either direction.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization

of these instrumentalities as herein shown 55 and described.

Figure 1 represents a fragmentary vertical cross section of a dyeing machine equipped with my novel snubbing device embodying my present invention. 60

Figure 2 represents an enlarged fragmentary detail perspective view showing the mounting of one stick, its snubbing device and associated parts.

Figure 3 represents an enlarged face view 65 of the parts shown in Figure 2.

Figure 4 represents a diametrical sectional view taken on the line 4—4 of Figure 3.

Figure 5 represents a fragmentary elevation of a spring forming part of the snubbing device. 70

Similar numerals of reference indicate corresponding parts in the figures.

Referring to the drawings:

1 designates a portion of a reel adapted 75 to be arranged in a suitable dye tub or vat, not shown, and 2 designates a well known tripping device employed.

3 designates a hub which is attached to the collar 4, the former being mounted on 80 the driving shaft 6 and the latter being secured as at 5 to one of the spiders or spokes 7 of the reel, which latter supports inner and outer bearing rings 8 and 9. The reel is adapted to be suitably driven or rotated on 85 the shaft 6 and as shown, the outer ring 9 is in the form of a gear having teeth 10 adapted to mesh with a suitable pinion, by which it may be revolved. The resilient tripping device 2 provided is suitably supported 90 in the vat.

The bearing rings 8 and 9 are oppositely arranged and provided on each end of the reel with bearings for two parallel inner and outer concentric circular series of dyesticks 95 11 and 12. The inner sticks are preferably round in cross section while the outer sticks are preferably angular or square in cross section, and the skeins of yarn to be dyed are suspended and stretched between the 100 sticks or members of the outer and inner series or double reels, as indicated in dotted lines in Figure 1 of the drawings.

Each outer or angular stick is rotatably mounted at one end, as shown and described 105 in the patent above mentioned, being preferably provided on one end with a round ferrule not shown and on the other with a

square ferrule 13. The gear ring 9 is provided with a series of equidistantly spaced circular apertures 14 and bosses 15 projecting laterally therefrom around the aperture walls. The stick is held on the round end in a journal so constructed that the stick may be readily put in place or removed, while at the other or square end provided with ferrule 13 a socket bearing or ratchet cup 16 is provided journaled in ring 9 and having a square socket 17 receiving and supporting the squared end in fixed relation thereto. The cup 16 is of circular cross section mounted in apertures 14, provided at 15 one end with a ratchet or star wheel 18, at the inner end of socket 17 with an internal annular stop shoulder or flange 19 and at the other end with an external circumscribing rib 20.

20 Bosses 15 form spacers between the star wheels 18 and gear ring 9. A retainer 21 is seated on the barrel of cup 16 against ring 9 to retain the cup in position, and a helical spring 22 preferably of wire or square cross section is wrapped or snugly mounted around the barrel of the cup, which is turned to a smooth cylinder, one end of the spring being made fast to the ratchet cup supporting members or ring 9 and the other 25 end abutting shoulder 20. As illustrated, the spring ratchet forming a part of the snubbing device or gripper, is composed of several coils and has its terminals provided with eyes 23 and 24, the former of which 30 is anchored to the ring 9 as indicated at 25 and the latter of which is free, but preferably bent slightly inwardly with the last or adjacent coil, as indicated at 26.

In the operation of the machine, the reel 40 is driven as described, or in any other customary way, and as the star wheels pass the tripper T, each star wheel and its outer stick is "tripped" or given a quarter turn to move the yarn a corresponding distance so 45 that all parts of the skein will have equal exposure to the dye liquor as previously stated. The tripper will operate in the usual way, the spring of the trip device taking up jar or shock. As the star or ratchet wheels 18 are 50 tripped, and the sleeves or cups 16 turned, the outer dyesticks 12 will be correspondingly turned to impart the necessary movement to the yarn, this being facilitated by the 55 square cross-section of the sticks and the conformation and fitting grip of the yarn thereto. In all prior machines, retrograde rotation of the journaled socket bearings or cups was prevented by spring or gravity-actuated pawls, which are not only readily worn 60 and soon become inoperative for the purpose intended, but do not permit turning of the cup or bearing socket in a backward direction when desired. By the present device rotation of the cup and stick in a forward direction is permitted, but when tension of the

yarn acts to cause backward motion, the coils of the spring, due to the friction between the spring and barrel wraps tightly on the barrel of the cup and grips or seizes it so tightly as to prevent any backward motion. The principle of action is the same as snubbing a rope around a post, in which a flexible member surrounds a cylindrical form to prevent rotation of the cylinder in one direction and permit rotation in the opposite direction. Several coils of wire are necessary to produce the desired effect, but it is found in practice that by bending the last coil, which has the free eye 25, slightly toward the center of the coil and stepping or canting the coils, a fewer number of coils is required. At times, it is desirable to turn the cup in a backward direction, and for this purpose, eye 24 is provided on the end of the free or last coil of the spring, so that the end of the spring may, when desired, be manually lifted away from the ratchet cup barrel, when the bearing socket or cup and stick, as well as the yarn, may be readily moved in a backward direction. While the snubbing device is shown applied to a dyeing machine, it may be applied, and the scope of the invention includes its application, to any like device, but more especially to machines for chemically treating spinnable material; chemical treatment including any treatment by which the condition of the material is changed in nature or appearance, weight or degree of moisture, such as dyeing, bleaching, scouring, rinsing, drying, mercerizing, weighing etc., and spinnable material is understood to be any material which may be spun into a yarn or made into a filament.

Having thus described my invention, what I claim as new and desire to secure by Letters Patent, is:-

1. In a machine for chemically treating spinnable material, a stick adapted to support a skein, a stick rotating member, and a snubbing member arranged to prevent rotation in one direction and to permit rotation in the opposite direction.

2. In a machine for chemically treating spinnable material, a stick, a stick rotating member, a snubbing member arranged to normally prevent rotation of said stick in one direction and to permit its rotation in the opposite direction, and means for enabling said stick to be rotated in either direction when desired.

3. The combination of a stick, a stick turning mechanism for dyeing, bleaching and scouring machinery, means surrounding the stick turning means and frictionally gripping the same in one direction to prevent retrograde motion thereof and adapted to permit motion thereof in the opposite direction, and means for enabling said stick to be rotated in either direction.

4. The combination of a stick, a stick turning mechanism for dyeing, bleaching and scouring machinery, and means surrounding the stick turning means and frictionally gripping the same in one direction to prevent retrograde motion thereof and adapted to permit motion thereof in the opposite direction, said means including an element fixed to said stick and an expandable element on the fixed element and held against bodily movement.
5. The combination of a stick, a stick turning mechanism for dyeing, bleaching and scouring machinery, and means surrounding the stick turning means and frictionally gripping the same in one direction to prevent retrograde motion thereof and adapted to permit motion thereof in the opposite direction, said means including a cylindrical element fixed to said stick, and a spring snug on said cylindrical element and anchored at one end, to grip said element in one direction and release it in the opposite direction to permit or prevent turning of said stick.
